HOOK-ON ELECTRICAL INSTRUMENT

Roger B. Kerr, Topsfield, Mass., assignor to General Electric Company, a corporation of New York

Filed Aug. 28, 1961, Ser. No. 66,518

Term of patent 14 years

(Cl. D26—1)

FIG. 1 is a perspective view of a hook-on electrical instrument showing my new design;

FIG. 2 is a front elevation in an enlarged scale;

FIG. 3 is a right side elevation in the same enlarged scale;

FIG. 4 is a bottom view in the same enlarged scale; and

FIG. 5 is a rear elevation thereof.

The broken line partial showing of the cords is for illustrative purposes only.

I claim:

The ornamental design for a hook-on electrical instrument, as shown and described.
